5 Claims. (Cl. 260—633.2)

1

This application is a continuation-in-part of my co-pending application Serial Number 706,057 filed October 28, 1946.

This invention relates to a process for isomerizing olefinic hydrocarbons and particularly for isomerizing alkenes.

An object of this invention is to isomerize an olefinic hydrocarbon.

Another object of this invention is to isomerize an alkene having at least four carbon atoms per molecule.

In one embodiment, this invention relates to a process for isomerizing olefinic hydrocarbons which comprises contacting an olefinic hydrocarbon having at least four carbon atoms per molecule at conversion conditions with an ammonium phosphate.

In another embodiment, this invention relates to a process for isomerizing olefinic hydrocarbons which comprises contacting an olefinic hydrocarbon having at least four carbon atoms per molecule at conversion conditions with a composite of ammonium phosphate and a solid carrier.

Olefinic hydrocarbons utilizable in this process comprise monoolefins having one double bond per molecule and polyolefins which have more than one double bond per molecule. Monoolefins which are preferred as starting materials for this process have at least four carbon atoms per molecule and include butylenes, pentenes, and higher molecular weight normally liquid olefins, the latter including various polymers of normally gaseous olefins. Cycloolefins such as cyclopentene, cyclohexene, and various cycloolefins may also be used but not necessarily under the same conditions of operation as employed with open chain olefins which may also be referred to as alkenes.

Catalysts useful in promoting an isomerization of olefinic hydrocarbons comprise ammonium salts of phosphoric acids. These ammonium salts include both neutral and acid salts of ortho-, pyro-, tri-, tetra-, and other polyphosphoric acids, as such, in admixture with one another and also supported on solid carriers, such as a siliceous carrier as silica, diatomaceous earth, fuller's earth, crushed porcelain, etc., and also alumina, charcoal, and other packing materials which do not interfere with the desired catalytic activity of an ammonium phosphate. Composites of an ammonium salt of an acid of phosphorus and a carrier, such as diatomaceous earth or some other siliceous material, are preferably calcined before being utilized as catalysts

2

in conversion reactions of organic compounds and particularly of hydrocarbons. Such calcination is generally carried out at a temperature of about 200° to about 500° C.

According to the process of the present invention, an olefinic hydrocarbon may be reacted in the presence of an ammonium phosphate catalyst at a temperature of from about 150° C. to about 450° C. to produce isomeric olefins including branched chain and straight chain olefins. The isomerization of a straight chain olefinic in the presence of an ammonium phosphate yields a branched chain olefin as a result of so-called skeletal isomerization of the charged olefinic hydrocarbons. The isomerization reaction may also involve the shifting of the position of the double bond along the carbon chain of the olefinic hydrocarbon. Thus a shift of the double bond occurs when 1-butylene is converted into 2-butylene whereas skeletal isomerization occurs during the conversion of either of the straight chain olefins, 1-butylene and 2-butylene, into the branched chain olefin isobutylene, this being an example of the so-called skeletal isomerization.

25 Olefin isomerization in the presence of a catalyst comprising an ammonium phosphate as its essential active ingredient, is carried out preferably at a temperature of from about 150° to about 350° C., particularly since the higher temperature of the broader range, namely, from about 150° to about 450° C., sometimes result in certain amounts of decomposition, cracking, and hydrogen transfer reactions. The process is also carried out generally at atmospheric pressure, although higher conversions may sometimes be obtained at subatmospheric pressure while increased capacity results when the process is effected at a slight superatmospheric pressure which is generally not more than about 5 atmospheres. At a superatmospheric pressure, a certain amount of olefin polymerization takes place with the result that the yield of isomerized olefin is decreased.

45 The process of the present invention is carried out in either batch or continuous types of operation. Thus in a simple batch type process, the olefin containing at least four carbon atoms per molecule is brought to a reaction temperature as specified above in the presence of an ammonium phosphate or of a solid composite of an ammonium phosphate and a suitable carrier or supporting material while the reaction mixture is stirred mechanically to effect intimate contact between the catalyst and the olefinic 50 hydrocarbon charging stock.

The resultant mixture of olefinic hydrocarbons and catalyst is removed periodically from the batch reactor, the catalyst is separated and the hydrocarbon product is fractionally distilled to separate the isomerization product from unconverted (unisomerized) olefinic hydrocarbon which is recycled to the process. One method of effecting this separation of the reaction products involves filtration to remove the catalyst from the hydrocarbons and fractional distillation of the hydrocarbons, whereby unconverted isomerizable hydrocarbon material is vaporized and distilled from the isomerized olefinic material. The recovered isomerizable olefinic hydrocarbon and catalyst are then returned to the reaction zone for further treatment, while the isomerization product is fractionally distilled to separate desired fractions therefrom.

I prefer to carry out this olefin isomerization reaction in a continuous manner; thus in the isomerization of an olefinic hydrocarbon in the presence of a solid catalyst, there is withdrawn from the isomerization reactor a mixture of isomerized olefinic hydrocarbons and unconverted olefinic hydrocarbons. The isomerization reaction may also be carried out by introducing an olefinic hydrocarbon and catalyst or a mixture of olefinic hydrocarbons and catalyst, said catalyst in finely divided form, to a coil or tower provided with baffles, orifice plates, or other mixing devices or a vessel provided with a stirrer or other mechanical means of agitation, although any method may be employed that satisfactorily effects intimate contact of the charged olefinic hydrocarbons and catalyst. Thus the various batch or continuous types of isomerization may use either finely divided catalyst or one or more fixed beds of a solid catalyst composite comprising an ammonium phosphate as its essential active ingredient.

The following examples are given to indicate results obtainable by the use of the present process, although they are not intended to limit the scope of the invention in exact correspondence therewith.

Example I

A mixture of 30% 1-butylene and 70% n-butane is contacted with a triammonium phosphate-diatomaceous earth composite at 300° C. and atmospheric pressure. When using average contact time of from 2 to 30 seconds, a butane-butylene mixture is recovered containing 70% butane and 30% normal butylenes, more than half of the latter being 2-butylene.

Example II

A mixture of normal pentene comprising pentene-1 and pentene-2 is passed through a reactor containing a granular solid composite of 70% by weight of triammonium phosphate and

30% by weight of diatomaceous earth maintained at a temperature of 375° C. and atmospheric pressure. The mixture of normal pentenes is passed through the reactor at a liquid hourly space velocity of 2. The liquid hydrocarbons recovered from the outlet end of the reactor, representing 95% of the pentenes charged, contain 20 mole per cent of branched chain pentenes admixed with normal pentenes. The branched chain pentenes include 2-methyl-1-butene, 3-methyl-1-butene and 2-methyl-2-butene.

I claim as my invention:

1. A process for isomerizing olefinic hydrocarbons which comprises contacting an olefinic hydrocarbon having at least four carbon atoms per molecule at isomerizing conditions with an ammonium phosphate.

2. A process for isomerizing olefinic hydrocarbons which comprises contacting an olefinic hydrocarbon having at least four carbon atoms per molecule at a temperature of from about 150° to about 450° C. with a catalyst comprising an ammonium phosphate as its essential active ingredient.

3. A process for isomerizing olefinic hydrocarbons which comprises contacting an olefinic hydrocarbon having at least four carbon atoms per molecule at isomerizing conditions with a composite of ammonium phosphate and a solid carrier.

4. A process for isomerizing olefinic hydrocarbons which comprises contacting an olefinic hydrocarbon having at least four carbon atoms per molecule at a temperature of from about 150° to about 450° C. with a composite of ammonium phosphate and a solid carrier.

5. A process for isomerizing olefinic hydrocarbons which comprises contacting an olefinic hydrocarbon having at least four carbon atoms per molecule at a temperature of from about 150° to about 450° C. with a composite of ammonium phosphate and diatomaceous earth.

RAYMOND E. SCHAAD.
